UNITED STATES PATENT OFFICE.

JOHN JAY GREEN, OF BOONTON, ASSIGNOR TO THE SECURITY INSULATOR COMPANY, OF ELIZABETH, NEW JERSEY.

CEILING-BLOCK.

SPECIFICATION forming part of Letters Patent No. 484,911, dated October 25, 1892.

Application filed May 17, 1892. Serial No. 433,267. (No model.)

To all whom it may concern:

Be it known that I, JOHN JAY GREEN, a citizen of the United States, residing at Boonton, in the county of Morris and State of New Jersey, have invented certain new and useful Improvements in Fuse-Blocks for Electric Wires, of which the following is a specification.

My invention relates to a device termed a "fuse-block," which is placed at the point of junction between the main wires of an electrical distributing circuit and the branch or consumption wires leading to a translating device, such as an electric lamp or motor. Such a fuse-block consists, usually, of a closed case or box of incombustible material formed of a base-piece and a cover fitted thereto, within which are placed two pairs of metallic terminals or clamps, one pair for the main and the other pair for the branch wires, these being respectively united by means of "fuse-wires," the thicknesses of which are adjusted in such relation to the current intended to be carried to the translating device that in case of an excess of current they will be fused and will interrupt the circuit.

The object of my invention is to provide a fuse-block which shall effectually exclude air or moisture from the terminals and connections of the wires at the points of junction inclosed therein, and which may therefore be used in chemical manufactories, salt-works, and other like places in which the atmospheric and other conditions are destructive to the integrity of the wires and connections when inclosed in a fuse-block of ordinary construction.

In the accompanying drawings, Figure 1 is a transverse vertical section of a "ceiling-pendant" fuse-block embodying my invention, taken in the plane of the dotted line 1 1 in Fig. 3. Fig. 2 is a cross-section of the same, taken in the plane of the line 2 2 in Fig. 1. Fig. 3 is an inverted plan of the base with the cap removed; and Fig. 4 is a plan view of the cap, showing the arrangement of the fuse connections attached to the same.

The particular form of the device which I have selected for illustration of my invention is termed a "ceiling fuse-block," being

usually affixed to a ceiling in order to permit of the attachment, for example, of a pendent incandescent lamp. The incombustible base A, preferably of porcelain or glass, is secured to the ceiling by wood-screws passing through the countersunk holes a a. It is preferably circular in form and contains a chamber B, surrounded by a flat circular bearing-surface a'.

D is a cover, of the same material as the base, and also preferably circular in form. This cover is provided with a similar flat bearing-surface d' and is secured in position by ears d d, which interlock with grooved projections a² a², formed on the base A, as hereinafter explained. Before putting the cover D in place a compressible and preferably elastic packing—as, for example, a ring of india-rubber—is placed between the opposite flat bearing-surfaces a' and d', as shown at C. The cover D is then put on by pressing it against the packing and laterally rotating it, so that the ears d d, which have beveled or inclined edges, as shown in Fig. 2, will pass laterally into the grooves a³, and thus exert a compressive action upon the packing C, forming a tight joint impervious to air, water, or steam and absolutely protecting the interior from the ingress of moisture in any form. Within this interior chamber B are placed the metallic terminals and connections F F of the electric conductors E E, which conduct the current from the main line to the branch. These terminals F F are secured to the base A by screws or otherwise and are provided with spring-contacts f f. The branch or consumption wires L L, which lead to the translating device, are attached to metallic terminals K K, secured to the inside of the cover D by screws or otherwise. The fuse-terminals H H are L-shaped and their projecting portions h h enter behind the contact-springs f f when the cap is laterally rotated in the manner hereinbefore explained, in order to secure the cap to the base. The contact-springs f f after the cap has been thus rotated press against the fuse-terminals H H by virtue of their inherent resiliency. As the fuses I I are clamped between the terminals H H and the terminals K K, it will be under-

stood that when the cap D is laterally rotated into position, so that its ears will interlock with the projections upon the base, the electrical connections will simultaneously be completed within the chamber B by the contact of the projections *h h* with the contact springs *ff* in the manner hereinbefore explained. The central opening through which the consumption-wires L L pass out from the chamber B through the cap D terminates in a tube, as shown in A' in Fig. 1, upon which tube may be drawn one end of an elastic rubber or other like tube M of any required length, thus enabling the wires L L to be completely protected by a sheath, which forms an air-tight joint with the cap D, and extends, if required, to the translating device.

An air-tight packing of any suitable material is applied to the apertures *e e*, through which the conductors E E are led into the chamber B of the base. The countersunk apertures for the admission of screws for fastening the terminals to the base may also

with advantage be sealed with paraffine-wax or other like material.

25

I claim as my invention—

In a fuse-block for electric wires, the combination of the hollow base inclosing the terminals of the main wires, the cap fitted thereto carrying the terminals of the consumption-wires, the compressible packing inserted between said base and cap, the interlocking projections upon said base and cap for securing them together, and the interlocking terminals of the main and consumption wires, whereby the electric circuit is completed by the act of rotating the cap laterally into position to compress the packing, as set forth.

In testimony whereof I have hereunto subscribed my name this 2d day of May, A. D. 40 1892.

JOHN JAY GREEN.
